UNITED STATES PATENT OFFICE.

JOHANN G. PETERSON, OF JERSEY CITY, NEW JERSEY, ASSIGNEE TO MANHATTAN ELECTRICAL SUPPLY COMPANY, OF JERSEY CITY, NEW JERSEY, A CORPORATION OF NEW JERSEY.

RATCHET MECHANISM FOR ELECTRIC SWITCHES.

1,108,516.

Specification of Letters Patent. Patented Aug. 25, 1914.

Application filed March 30, 1914. Serial No. 828,231.

To all whom it may concern:

Be it known that I, JOHANN G. PETERSON, a citizen of the United States, residing at Jersey City, in the county of Hudson and 5 State of New Jersey, have invented certain new and useful Improvements in Ratchet Mechanism for Electric Switches, of which the following is a specification.

This invention relates to ratchet mechanism for electric switches, the object of the 10 invention being the provision of simple and effective means for compensating for wear or unevenness in or crumbling away of the porcelain or equivalent body of the switch, 15 so that under any one of these conditions the ratchet can be securely maintained in proper relation with said body.

In the drawings accompanying and forming part of the present specification I have 20 shown in detail one of the several convenient forms of embodiment of the invention, which to enable those skilled in the art to practice the same will be set forth fully in the following description. I do not restrict 25 myself to this disclosure; I may depart therefrom in several respects within the scope of the invention defined by the claims following said description.

Referring to said drawings: Figure 1 is 30 a top plan view of the supporting body of an electric switch provided with ratchet mechanism involving my invention. Fig. 2 is a cross section on the line 2—2 of Fig. 1. Fig. 3 is a plan view of a washer hereinafter 35 more particularly described, and, Fig. 4 is a cross section of said washer.

Like characters refer to like parts throughout the several figures.

My ratchet mechanism can be employed 40 with advantage in connection with any of the existing forms of switches one of which is illustrated in Patent No. 1,077,746 granted to me November 4, 1913. In the drawings I have shown the body 2 of said 45 switch. This body may be made of porcelain or other suitable material. A switch such as that shown in said Letters Patent comprises a stationary ratchet connected with one end of a bushing, the other end 50 of the bushing or equivalent being provided with a washer fitted against the under side of the body of porcelain or other suitable non-conducting, fictile material. The space between the ratchet and the washer varies

and some times the porcelain or other substance between the two crumbles or wears away, and in each of these cases there is looseness between the washer and the ratchet to such an extent as to prevent proper action. By my construction I eliminate any movement of the ratchet and hold it rigidly and substantially against its seat under all conditions; that is if there should be wear or crumbling away at the place indicated, the means involving my invention will compensate therefor and will also insure rigidity of the ratchet should there be variations in size of the porcelain body.

The numeral 3 denotes a ratchet which is mounted on the ratchet plate 4 both located 70 in the counterbore 5 in the upper side of the porcelain body 2, the two parts being rigidly secured to each other by projections 6 punched from the ratchet and closely fitting holes 7 in the ratchet plate. Said ratchet 75 plate is provided at suitable points upon its rim with downwardly extending barbs or projections 8 fitted in sockets 9 in the bottom of the counterbore 5. The ratchet 3 and ratchet plate 4 have central registering perforations to receive the upper end of the bushing 10 which is connected with the parts by being expanded as at 11 at its upper end.

The foregoing construction is shown 85 practically in the Letters Patent to which I have alluded, and the invention does not in itself concern the same but in means for holding the ratchet 3 properly in place and for compensating for wear and unevenness 90 as already described. The bushing 10 constituting a suitable connecting stud, extends through a hole in the web or wall 12 between the upper counterbore 5 and the lower counterbore 13, its lower end extending 95 through a central perforation in the washer 14, the bushing being held rigidly to said counterbore by being expanded as at 15 at its lower end. It should be understood that I use the expression "upper" and "lower" 100 merely for convenience. If the switch be set as shown in the drawings these terms will apply, but if it be inverted what is now described as upper will be lower and vice versa. The washer 14 which is usually 105 stamped from sheet metal, for compactness fits an auxiliary counterbore 16 opening into the counterbore 13, although in all

cases this might not be necessary. This washer is provided with yieldable means acting against the body 2 to constantly draw the ratchet 3 downwardly or against its seat which may be against the plate 4 or otherwise. Said yieldable means may be of any desirable character, although with advantage they consist of one or more springs forming an integral part of the washer 14, so that the washer, therefore, serves a double function. Said washer is shown having cut into its peripheral portion several approximately L-shaped slits thereby producing the resilient or spring tongues 17, there being three of such spring tongues and which in the construction shown have their free portions deflected upwardly. In other words the free ends of the spring tongues bear directly against the porcelain body 2 so as to apply a constant downward pull to the ratchet 3 and thereby obtain the advantages to which I have referred.

What I claim is:

1. An electric switch comprising a body of non-conducting, fictile material, said body having a seat, a ratchet to fit against said seat, a washer having several spring fingers slit therefrom, the free ends of the fingers acting against the body of the

switch, and a connection between the washer 30 and the ratchet to cause the washer to constantly draw the ratchet against said seat.

2. An electric switch comprising a body of non-conducting, fictile material, a ratchet, the body having a seat for the ratchet, and a washer connected with the ratchet and provided with spring means acting against said body, to constantly draw said ratchet against said seat.

3. An electric switch comprising a body 40 of non-conducting, fictile material, a ratchet, the body having a seat for the ratchet, and yieldable means acting constantly against the ratchet to draw the same against its seat.

4. An electric switch comprising a body 45 of non-conducting, fictile material, a ratchet, the body having a seat for the ratchet, a stud connected with the ratchet, the body having an opening for the passage of the stud, and spring means connected with the 50 stud and acting against the body to draw the ratchet constantly against said seat.

In testimony whereof I affix my signature in presence of two witnesses.

JOHANN G. PETERSON.
